UNITED STATES PATENT OFFICE

2,503,946

GOVERNOR FOR ENGINES

Elton C. Hallett, Los Angeles, Calif., assignor, by
mesne assignments, to Hallett Manufacturing
Company, Inglewood, Calif., a corporation of
California

Application April 15, 1946; Serial No. 662,197

6 Claims. (Cl. 123—104)

1

The invention relates to governors and has particular reference to governors which are used to regulate combustion engines.

In the use of governors on engines for limiting or controlling the speed or output much attention has been directed to the provision of governors of the flyball type which operate by the action of centrifugal force upon weighted rotating elements. Flyball governors, however, possess some limitations in that they do not respond with sufficient rapidity at all speeds and do not lend themselves with sufficient ease to adjustment while in operation.

It is, therefore, among the objects of the invention to provide a new and improved governor which is sensitive and positive in its action and which can be accurately adjusted while the engine is in operation.

Another object of the invention is to provide a new and improved governor device for combustion engines which is simple and inexpensive to manufacture and which utilizes as a part of the governor mechanism portions of the engine mechanism which are devoted to other purposes.

Still another object of the invention is to provide a combustion engine governor which is rugged in construction so that it will continue to operate satisfactorily under adverse conditions over long periods of time.

Still further among the objects of the invention is to provide a new and improved governor which is so constructed that most of its operating parts may be readily concealed in locations where they cannot readily become misadjusted or disturbed and which incorporates a sensitive adjustment which is easily accessible and capable of altering the adjustment of the governor at any time.

With these and other objects in view, the invention consists in the construction, arrangement and combination of the various parts of the device whereby the objects contemplated are attained, as hereinafter more fully set forth, pointed out in the claims and illustrated in the accompanying drawings, in which:

Figure 1 is a fragmentary, side, elevational view of a combustion engine showing the portion of the device devoted to the governor partly in section.

Figure 2 is a fragmentary, cross-sectional view taken on the line 2—2 of Figure 1.

Figure 3 is a cross-sectional view of the adjusting portion of the governor taken on the line 3—3 of Figure 2.

Figure 4 is a plan view of a detent for holding the governor adjusting handle in position.

2

Combustion engines and particularly Diesel engines in recent years have been adapted to a great variety of uses under all sorts of operating conditions. As the engine of standard specifications continues to be pressed into services somewhat different from those for which the engine has been designed increased care must be taken in making sure that the operating parts are of such construction that they will continue to function efficiently under all circumstances. Since the redesign of the engine itself is an expensive undertaking, where some changes must be made it becomes advisable to retain the design of the engine itself and make the necessary changes and improvements in some of the operating or accessory parts, thus preserving the original design of the engine. If the changed operating parts are to be successfully utilized, they must be positive in operation under all sorts of conditions and must likewise be of such simple construction that they can be readily incorporated into engines of standard construction and design.

In an embodiment chosen to illustrate the improved type of governor comprising this invention there has been selected, by way of example, a combustion engine which may be, for example, a Diesel type engine, comprising an engine block 10. Mounted in the engine block is a crank shaft 11 which supports a flywheel 12.

30 Above the engine block is a cylinder block 13.

On the side of the engine block between the flywheel and the engine there is provided a casing 14 through which the crank shaft passes. Within the casing and attached to the crank shaft is a gear 15 which is positioned so that it meshes with a gear 17, frequently of twice the diameter and number of teeth, the second gear being keyed to a cam shaft 18, the cam shaft being for the usual purpose of manipulating valves and fuel injectors for the engine.

40 The gear 17, as here shown, is provided with a shallow depression 20 facing outwardly relative to the engine block. Within the depression are mounted counterweight or flyball elements 21

45 which have a somewhat L shape and which are secured by pivot pins 22 to an appropriate boss 23 within the depression of the gear 17. Each of the two counterweights shown incorporate a weighted end 28 which is free to pivot outwardly and inwardly and a lever end 24. The lever end is positioned in endwise contact with an inwardly facing annular edge 25 of a cap 26. The cap 26 has a bottom 27 facing outwardly relative to the shallow depression. As shown, the cap is 50 mounted over the end of the cam shaft 18 so

that it is free to rotate about the shaft and to shift axially relative to the shaft. Movement of the cap is in response to pivotal movement of the counterweights or flyballs, and it will be noted that the counterweights are balanced about the axis of the gear 17.

In order to transfer the axial motion of the cap 26 to some appropriate location where it may be used for governing purposes, there is provided a linkage 30 which incorporates a lever arm 31 pivotally mounted upon a pivot pin 32 which is journaled in lugs 33 on the engine block. The pivot pin is rotatably mounted in flanges 34 and extends into a casing or housing 35. Link elements 36, 37 and 38 make up a portion of the linkage which is adapted to extend to a fuel supply for the engine. The element 36 is fastened non-rotatably to the pivot pin 32 so that it is adapted to be moved when the pivot pin rotates.

For setting the governor there is provided a coiled spring 40, one end of which is mounted upon a trunnion or spring keeper 41 and is anchored together with the trunnion to the pin 32 by means of a lock pin 43. In the opposite end of the casing 35 a stub shaft 44 is non-rotatably fixed, and upon the stub shaft is rotatably mounted a worm gear 45. A trunnion or spring keeper 46 adjacent the worm gear provides a mounting for the adjacent end of the coiled spring. It will be noted that the spring has a turned down end 47 fastened to the worm gear so that the spring is rotated whenever the worm gear is rotated.

To provide a manual adjustment for the worm gear a stem 48 extends into the casing spaced from and transverse to the axis of the stub shaft 44. Upon the stem is a worm wheel 49 attached thereto by means of a pin 50, the worm wheel being adjusted to mesh with the worm gear 45. The stem 48 extends upwardly from the casing and is provided with a handle 51.

So that the handle may be held in a desired position there is provided a temporary detent 52 which may be a somewhat V-shaped, resilient member which is fastened to the top of the casing by some convenient means such as a rivet or screw 53. One side of the V-shaped member may be adapted to engage one or another of the flats 54 on an extended portion of the stem so that the stem will not accidentally rotate out of adjustment.

In operation of the device herein described wherein the gear 15 is one-half the diameter of the gear 17 the crank shaft rotates the cam shaft at one-half the rate of its own rotation. As the gear 17 rotates centrifugal force acting upon the weights 23 tends to pivot the weights about their respective pins 22 in an outward direction. This action tends to move the lever ends 24 against the cap and to lift the cap from its normal position. That is to say, the cap is moved axially from right to left as viewed in Figure 1.

Movement of the cap is transferred to the lever arm 31 which is rotated and which in turn, being keyed to the pin 32, rotates the pin 32 clockwise as viewed in Figure 1. This will tend to move the linkage 30 from left to right and make a corresponding adjustment on whatever fuel feeding device the linkage is connected to.

To modify action of the governor it is necessary only to rotate the handle 51 in one direction or another to either increase or decrease tension on the coiled spring 40. This will react more or less against the tilting of the counterweights. Movement of the cap 26 will thus be either increased or decreased depending on the direction

of the setting and will effect a corresponding movement one way or the other in the linkage 30.

By the arrangement shown there has been provided a governor device which may be incorporated bodily into the gear which drives the cam shaft and which occupies a compact space safely removed to a position within the confines of the engine. A sensitive adjustment keeps the governor under control at all times. The parts are relatively few and simply constructed so that they operate readily with high efficiency and can at the same time be adjusted with a high degree of precision.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent structures.

The invention having been herein described, what is claimed and sought to be secured by Letters Patent is:

25. In an engine a governor adjustment comprising an engine block, a linkage pivotally mounted on the block and a spring tension member cooperable therewith, said spring tension member comprising a rotating member included in said linkage and a spring having one end non-rotatably attached to said member, a stub shaft mounted upon the block and the other end of said spring being mounted in guiding relationship with the stub shaft, a stem and an endless rotatable adjusting attachment between the stem and the other end of the spring.
30. In an engine a governor adjustment comprising an engine block, a linkage, a pivot pin rotatably mounted on the block for mounting the linkage and a spring tension member cooperable therewith, said spring tension member incorporating the pivot pin, a coiled spring having one end non-rotatably attached to said pivot pin, a stub shaft mounted upon the engine block and the other end of said spring being mounted around the stub shaft, a gear on said stub shaft attached to the spring, a stem mounted on the block having a worm wheel thereon meshing with the gear, and a handle element on the stem.
35. In an engine a governor adjustment comprising an engine block, a linkage, a pivot pin rotatably mounted on the block for mounting the linkage and a spring tension member cooperable therewith, said spring tension member incorporating the pivot pin, a coiled spring having one end non-rotatably attached to said pivot pin, a stub shaft mounted upon the engine block and the other end of said spring being mounted around the stub shaft, a gear on said stub shaft attached to the spring, a stem mounted on the block having a worm wheel thereon meshing with the gear, and a handle element on the stem.
40. In a Diesel engine incorporating an engine block, a drive shaft mounted on the block, a cam shaft, gears in driving relationship with the cam shaft and the drive shaft and a fuel injection means, the combination of a unitary governor control housed at one end of the engine block comprising a gear casing surrounding the gears and attached to the end of the engine block, a spring casing attached to the side of the gear casing, a counterweight governor element on the cam shaft including an axially movable counterweight responsive member on the cam shaft, a linkage responsive to movement of said member comprising a pin rotatably mounted on said casings having one end extending into the gear casing and the other end extending into the spring casing, a lever fixed on said one end engaging said member, means adapted to connect said pin intermediate the ends to the fuel injection means and spring adjusting means in said spring housing engaging said other end of the pin.
45. In a Diesel engine incorporating an engine block, a drive shaft mounted on the block, a cam shaft, gears in driving relationship with the cam shaft and the drive shaft and a fuel injection means, the combination of a unitary governor
50. In a Diesel engine incorporating an engine block, a drive shaft mounted on the block, a cam shaft, gears in driving relationship with the cam shaft and the drive shaft and a fuel injection means, the combination of a unitary governor control housed at one end of the engine block comprising a gear casing surrounding the gears and attached to the end of the engine block, a spring casing attached to the side of the gear casing, a counterweight governor element on the cam shaft including an axially movable counterweight responsive member on the cam shaft, a linkage responsive to movement of said member comprising a pin rotatably mounted on said casings having one end extending into the gear casing and the other end extending into the spring casing, a lever fixed on said one end engaging said member, means adapted to connect said pin intermediate the ends to the fuel injection means and spring adjusting means in said spring housing engaging said other end of the pin.
55. In a Diesel engine incorporating an engine block, a drive shaft mounted on the block, a cam shaft, gears in driving relationship with the cam shaft and the drive shaft and a fuel injection means, the combination of a unitary governor
60. In a Diesel engine incorporating an engine block, a drive shaft mounted on the block, a cam shaft, gears in driving relationship with the cam shaft and the drive shaft and a fuel injection means, the combination of a unitary governor
65. In a Diesel engine incorporating an engine block, a drive shaft mounted on the block, a cam shaft, gears in driving relationship with the cam shaft and the drive shaft and a fuel injection means, the combination of a unitary governor
70. In a Diesel engine incorporating an engine block, a drive shaft mounted on the block, a cam shaft, gears in driving relationship with the cam shaft and the drive shaft and a fuel injection means, the combination of a unitary governor
75. In a Diesel engine incorporating an engine block, a drive shaft mounted on the block, a cam shaft, gears in driving relationship with the cam shaft and the drive shaft and a fuel injection means, the combination of a unitary governor

control housed at one end of the engine block comprising a gear casing surrounding the gears and attached to the end of the engine block, a spring casing attached to the side of the gear casing in transverse position relative to the cam shaft, and spaced parallel flanges comprising portions of said casings, a counterweight governor element on the cam shaft including an axially movable counterweight responsive cap on the cam shaft, a linkage responsive to cap movement comprising a pin rotatably mounted in said flanges having one end extending into the gear casing and the other end extending into the spring casing, a lever fixed on said one end engaging said cap, means adapted to connect said pin at a location intermediate said flanges to the fuel injection means and spring adjusting means in said spring casing engaging said other end of the pin comprising a torsion spring connected at one end to said other end of the pin and a manually actuatable gear train attached to the other end of the spring.

5. In a Diesel engine incorporating an engine block, a drive shaft mounted on the block, a cam shaft, gears in driving relationship with the cam shaft and the drive shaft and a fuel injection means, the combination of a unitary governor control housed at one end of the engine block comprising a gear casing surrounding the gears and attached to the end of the engine block, a spring casing attached to the gear casing in transverse position relative to the cam shaft, a counterweight governor element on the cam shaft including an axially movable counterweight responsive cap on the cam shaft, a linkage responsive to cap movement comprising a pin rotatably mounted in adjacent walls of said casings having one end extending into the gear casing and the other end extending into the spring casing, a lever fixed on said one end engaging said cap, means adapted to connect said pin intermediate said ends to the fuel injection means and spring adjusting means in said spring housing engaging said other end of the pin comprising a stub shaft mounted in the housing, a gear mounted on the stub shaft, a gear rotating means in the housing having a manually actuated portion including a detent extending outside said spring housing and

a torsion spring having one end fixed to the pin and the other end fixed to the last identified gear.

6. In a Diesel engine incorporating an engine block, a drive shaft mounted on the block, a cam shaft, gears in driving relationship with the cam shaft and the drive shaft and a fuel injection means, the combination of a unitary governor control housed at one end of the engine block comprising a gear casing surrounding the gears and bolted to the end of the engine block, a spring casing bolted to the gear casing in transverse position relative to the cam shaft, and spaced parallel flanges comprising portions of said casings, a counterweight governor element on the cam shaft including an axially movable counterweight responsive cap on the cam shaft, a linkage responsive to cap movement comprising a pin rotatably mounted in said flanges having one end extending into the gear casing and the other end extending into the spring casing, a lever fixed on said one end engaging said cap, means adapted to connect said pin intermediate said flanges to the fuel injection means and spring adjusting means in said spring housing engaging said other end of the pin comprising a stub shaft fixed in the housing in axial alignment with the pin, a worm gear rotatably mounted on the stub shaft, a stem journaled in the spring casing and a worm wheel thereon engaging said last gear, a torsion spring having one end fixed to the pin and the other end surrounding one end of the stub shaft and fixed to the gear, and spring detent means on the spring casing releasably engaging said stem.
